UNITED STATES PATENT OFFICE.

BANCROFT B. BRITTS, OF BREAKERS, WASHINGTON.

HEEL AND INSTEP STIFFENER.

1,176,198.

Specification of Letters Patent. Patented Mar. 21, 1916.

Application filed June 19, 1915. Serial No. 35,048.

To all whom it may concern:

Be it known that I, BANCROFT B. BRITTS, a citizen of the United States, residing at Breakers, in the county of Pacific and State 5 of Washington, have invented a new and useful Heel and Instep Stiffener, of which the following is a specification.

The present invention appertains to a heel and instep stiffener or metallic counter 10 adapted to be disposed within or upon the exterior of the shoe, for stiffening or strengthening the heel or counter portion and instep portion of the shoe for purpose of wear, appearance, and comfort.

It is the object of the invention to provide a novel and improved article of that character adapted for use in various articles of foot wear.

With the foregoing and other objects in view, which will appear as the nature of the invention is better understood, the invention resides in the peculiar formation of the article as hereinafter set forth, it being understood, however, that slight changes 25 in details may be made, within the scope of what is claimed, without departing from the spirit of the invention.

The invention is illustrated in the accompanying drawing, wherein:

30 Figure 1 is a plan view of one form of the invention. Fig. 2 is a longitudinal section thereon taken on the line 2—2 of Fig. 1. Fig. 3 is a horizontal sectional detail taken on the line 3—3 of Fig. 2. Fig. 4 is a plan view of a second form of the invention. Fig. 5 is a longitudinal section on the line 5—5 of Fig. 4. Fig. 6 is a plan view of still another form.

In carrying out the invention, reference 40 being had to Figs. 1, 2 and 3, wherein one form of the invention is illustrated, there is provided a shank 1 formed from sheet metal, the entire article or stiffener depicted in said views, being formed from a single 45 blank of sheet metal, such as steel, or the like. The rear terminal of the shank 1 provides a bottom or heel plate 2 of the counter 3, and the forward terminal of the shank 1 may be extended, as at 4, to fit 50 between the insole and outsole for strengthening and protecting the same.

The counter 3 embodies upstanding sides 5 and 6 having their lower edges connected by means of strips 7 to the side edges of the bottom or heel plate 2, a pair of strips connecting each side of the counter and the bot-

tom or heel plate. The forward ends of the sides 5 and 6 of the counter may be extended so as to fit well into the instep portions of the upper, which is desirable. The rear 60 terminals of the sides 5 and 6 are curved inwardly and overlap, as at 8, and the rear end of the bottom or heel plate 2 is provided with an extension or tongue 9 projecting rearwardly therefrom. This tongue 65 9 passes under the overlapped portions 8, and is bent upwardly, as at 10, to rest against the outer side of the outer overlapping portion or terminal. The upper end of the upturned portion 10 is bent back 70 inwardly, as at 11, to engage over or around the upper edges of the overlapped portions 8, for holding said overlapped portions securely together. The rear terminal of the side 5 is bent back, as at 12, around the 75 respective edge of the upturned portion 10, to afford further securing.

The metallic shank and counter may be secured within the shoe during the construction thereof, or the device may be applied to the exterior of the shoe, whichever is desired by the user.

The form of stiffener illustrated in Figs. 1, 2 and 3, is preferably employed upon the exterior of the shoe, and it is to be noted 85 that this form may be readily bent from a blank of sheet metal, without the necessity of the metal being punched into shape by dies. This form is also adjustable, since the several parts thereof may be bent differently, to accommodate various sizes and 90 styles of shoes. The sides 5 and 6 of the counter project forwardly, or have forwardly projecting portions at the sides of and spaced from the shank 1, to strengthen 95 the instep. The shank 1 is relatively narrow and has its edges spaced from the forward ends of the sides, and the lower edges of the sides are spaced above the shank, so that the shank and forwardly projecting 100 portions of the sides can flex or bend freely independent of one another. The spacing of the sides and shank from one another also enables the lower edge of the upper to be stitched or otherwise fastened to the shank 105 of the shoe without the interference of the counter.

In the modified form illustrated in Figs. 4 and 5, the stiffener is punched from a blank of sheet aluminum or similar material, the stiffener embodying the shank 1' having the enlarged bottom or heel plate 2'

of the counter 3' at its rear end. In this form, the forward terminal of the shank 1' is cut shorter, as at 4', than the forward terminal 4 of the shank 1, although the shank 1' may be extended forwardly to any suitable point desired. The counter 3' has sides 5' and 6' upturned from the side edges of the plate 2', and has an upturned curved rear end 8' connecting the sides 5' and 6'.
10 The forward portion of the plate 2' is cut away, as at 13, between the shank 1' and the forward terminals of the sides 5' and 6', so that the said cut away portions will enable the respective parts of the shoe to be properly nailed or stitched together without interference. The nails for securing the heel in place may penetrate the plate 2'.

In the variation illustrated in Fig. 6, the stiffener eliminates the shank, and comprises 20 a counter 3^a constructed from sheet aluminum or other suitable metal, and having the bottom or heel plate 2^a provided with the upturned sides 5^a and 6^a and the upturned rear end 8^a connecting the sides and curved 25 to conform to the heel. The forward end of the plate 2^a is cut away, as at 13^a, to permit of nailing and stitching between the shank and heel of the shoe, and to allow the forward terminals of the sides to project 30 forwardly to the instep portion of the upper.

Having thus described the invention, what is claimed as new is:

1. A metallic counter embodying a heel plate having upturned sides, the rear terminals of said sides being inturned, and said plate having means at its rear end engaged to said inturned terminals for securing them together.
35

Copies of this patent may be obtained for five cents each, by addressing the "Commissioner of Patents, Washington, D. C."

2. A metallic counter embodying a heel plate having upturned sides, the rear terminals of said sides being inturned and overlapped, and the rear portion of said plate having means engaging said overlapped terminals for securing them together.
40

3. A metallic counter embodying a heel plate having upturned sides, the rear terminals of said sides being inturned and overlapped, and the rear portion of said plate having a tongue bent around said overlapped terminals for securing them together.
45

4. A metallic counter embodying a heel plate having upturned sides, the rear terminals of said sides being inturned and overlapped, and the rear portion of said plate having a tongue projecting therefrom, said tongue having an upturned portion in rear of said overlapped terminals, the upper end of said upturned portion being bent back over the upper edges of said overlapped terminals, and the outer terminal being bent 60 back around said upturned portion.
55

5. A sheet metal counter embodying a heel plate having upturned sides, and a forwardly projecting relatively narrow shank, the sides having forwardly projecting portions whose lower edges are spaced above the shank, the edges of the shank being spaced from said portions.
65

In testimony that I claim the foregoing as my own, I have hereto affixed my signature in the presence of two witnesses.
